UNITED STATES PATENT OFFICE.

EDWARD W. SCOWDEN, OF FREWSBURG, NEW YORK.

METHOD AND APPARATUS FOR CONCRETING PILES.

1,157,328.

Specification of Letters Patent.

Patented Oct. 19, 1915.

Application filed May 4, 1912. Serial No. 695,049.

To all whom it may concern:

Be it known that I, EDWARD W. SCOWDEN, citizen of the United States, residing at Frewsburg, in the county of Chautauqua and State of New York, have invented certain new and useful Improvements in Methods and Apparatus for Concreting Piles, of which the following is a specification.

10 This invention relates to an improved process and apparatus for placing a concrete sheathing around piling or other structures, to protect them from the ravages of destructive marine worms and the like, and 15 for the additional purposes of covering and reinforcing piling and such structures which have become eaten away by such marine worms.

This invention has for its primary object, 20 the adaptation to, and the applying of, concreting in its proper consistency, around the piling at a point below the level of the tide, without the interference of or commingling therewith of the surrounding sea water.

25 Another object of my invention is to lessen the cost and facilitate the application of the concreting, by the use of labor saving devices in mixing, conveying and depositing the concrete in its position.

30 These and further objects will more fully appear from the following description, in which reference will be made to the accompanying drawings which show a form of apparatus embodying my said invention, 35 wherein:

Figure 1, represents in side view, a form of apparatus comprising a reinforcing frame with the tubular mold in position therein. Fig. 2, represents a transverse section of the 40 reinforcing frame closed around the mold casing. Fig. 3, is a perspective view, with parts broken away of the reinforcing frame with the tubular mold casing in position therein. Fig. 4, is a view of the mold casing 45 and the reinforcing frame, bisected and opened, to facilitate closing around a pile. Fig. 5, shows my application of the concrete discharging apparatus in a connection with the mold casing and reinforcing frame placed around a pile. Fig. 6, is an enlarged 50 view of the bottom end of the casing placed in position, showing the discharging nozzle

with gasket attached thereto in the act of discharging concrete. Fig. 7, is an enlarged view of an expandible gasket, used in my apparatus. Fig. 8, is an enlarged view of the bottom section of the mold casing showing the jetting tubes.

Referring to the accompanying drawings, 55 1 represents a section of the tubular mold form, 2 represents a section of the reinforcing and supporting frame, 3 represents the hinge joint of the reinforcing frame which permits the frame to be opened to receive the tubular mold casing, 4 represents the latch by which the sides of the reinforcing frame opposite the hinge are locked together after closing into position, 5 represents the extended flange of the edges of the mold casing which are brought in proper contact 60 with the angle irons 7-7 of the reinforcing frame.

For the purposes of supporting and reinforcing the tubular mold sections, I use a suitable frame 2, surrounding the tubular 65 mold into which the concrete is placed as shown in Fig. 5.

In the construction of the supporting frame, the angle irons 7-7, are placed in pairs as shown in Fig. 3, and are so placed 70 in relation to each other, that the inwardly extended angles are so spaced apart as to permit of admitting the flange lips 5, of the tubular mold section to be placed between the inwardly extended faces of the angle 75 irons and thereby gripping the flange lips 5, in the closing operation of the reinforcing frame around the tubular mold. For the purpose of centering and supporting the mold casing within the frame, I provide 80 angle irons 6, which set into suitable pockets in the supporting frame.

For the purpose of supporting the tubular mold portion within the frame I provide 85 angle hooks 8, securely riveted to the tubular mold 1, at the upper and lower extremities thereof, and arranged to rest on the annular shaped hoop portions 9, of the reinforcing frame. For the purpose of handling the supporting frame, and swinging the same 90 into position around the pile or other structure, I provide hooks 10, securely attached to the supporting frame. To hooks 10, are attached a suitable chain 11, leading up-

ward to the superstructure 22, above the piling from which the apparatus is supported.

In providing a suitable tubular mold section which can be placed around a standing pile, I arrange for each section of the tubular mold form to be made in two half sections bisected vertically, the first section being reduced, funnel shaped at its lower end, 10 to facilitate its closing in around the bottom of the pile, and to better penetrate to bottom formation into which the pile is driven.

One of the objects of my invention is to make a contact at the bottom of the pile 15 where the mold casing penetrates the mud or sand which will exclude the water from coming into the casing from below. This penetration may be provided for by the weight of the tubular casing with the accompanying frame work being sufficient to cause the tapering end of the tubular casing to penetrate the ground foundation a sufficient distance to shut off the sea water, and prevent it penetrating the soil and following 20 the surface of the pile up into the interior of the mold. Where it is found that the soil formation at the bottom of the pile is of such nature that the tubular casing will not of its own weight, properly penetrate and make a water tight connection, the tubular casing with its frame work attached 25 may be caused to settle into the ground formation by the application of a jetting process a method well known in the art of marine excavations, and which I avail myself of in the operation of sinking the casing, by providing jetting tubes 12-12 placed along the outside of the casing.

To further facilitate the proper setting 40 of the concrete, and to avoid the intermingling thereof with the salt sea water, I provide a means of evacuating the sea water standing within the mold casing, after the casing has been sunk to the bottom, and 45 filling its place with fresh water, by means of connecting the discharging hose 13, with suitable source of fresh water supply, and forcing the salt water out of the mold by injecting fresh water under force, through 50 the hose 13 and discharging it at the lowest point of the mold. I further avail myself of this method of clarifying any water standing within the mold section, by substituting therefor, clean water having no 55 injurious ingredients which in any way affect or disintegrate the concrete in its setting process. After the casing has been sufficiently embedded in the ground formation around the pile, I provide for the lowering of a suitable hose 13, between the casing and the pile by leading the hose 13 from 60 the concrete ejecting apparatus 14, over the sheave 20, suspended from the superstructure 22. To the ejecting apparatus 14, suit-

able power, as an electric motor 15, is applied which forces the concrete through the hose 13, and allows the depositing thereof at such point as the nozzle 16, or discharge end of the hose may be applied.

Where it is found essential to provide for 70 a suitable shielding means between the water and the concrete being deposited around the pile, I provide an expandable gasket 17, through which the terminal of the hose 13 passes by the aperture 19, and 75 this gasket is so constructed that it can be opened and placed around a pile, and lowered with the concrete conveying means. As the concrete is forced through the hose and is ejected from the nozzle it will deposit 80 itself around the pile, and in doing so will force upward the gasket 17, separating the concrete from the water, thus maintaining a constant shielding means between the concrete being deposited and the water, which 85 is intended to prevent any agitation of the water above the concrete by which the salt water would commingle with the concrete, and cause a disintegration thereof or interfere with its proper setting.

As the concrete fills up the space between the mold and the pile, the water standing in the annular space between the pile in the mold will be gradually elevated, and will discharge itself automatically up over the 95 top of the casing. In this manner I am able to deposit a properly mixed column of concrete around a pile extending from the bottom thereof to a point above the water line without the detrimental intermingling of 100 sea water therewith. As the discharge nozzle of the concrete conveying hose, will always be discharging concrete at a point below the elevation of the top layer of concrete, there will always be a sufficient thickness of concrete above the discharge nozzle to keep the sea water from coming in contact with the concrete being deposited from the nozzle. The amount of the top layer of concrete so formed above the discharge 110 point of the nozzle may be varied by different forms of nozzle used. As the concrete is thus deposited within the annular space around the pile, and rises to a point above the level of the tide, such portions of 115 the top layer of concrete as may be found to be in any way affected by the salt water, may be removed, and its place filled with properly mixed concrete, which has in no way become affected, or been in contact with 120 the salt water.

It will be seen that one of the primary objects of my invention, is to place the concrete column around a pile without the commingling therewith of the surrounding sea 125 water, and in so doing, to utilize suitable conveying means by which this can be accomplished, without the necessity of apply-

ing hand labor to carry out these objects, and I avail myself of suitable means to accomplish this result.

The length of the tubular casing may be increased by the addition of sections necessary to extend from the mud line to a point above the surface of the water, and the internal diameter of the casing is in excess of the diameter of the pile to such an extent 10 as to provide an intervening annular space to conform with the thickness of the concrete coating to be placed around the pile.

The diaphragm or gasket 17, is of such construction that it may be opened and 15 placed around a standing pile which has already been driven into place and upon which a superstructure is supported. For the purpose of maintaining the proper shape, to the extent of closing around the pile in its 20 proper position an annular shaped spring 18, is placed within the gasket to cause it to adapt itself around the pile, and to adjust itself to the variations in the diameter of the pile, and in contour of the surfaces, so as to 25 substantially fill the annular space in which the concrete is placed, to such an extent as to prevent the sea water from freely commingling with the concrete. The diaphragm or gasket 17, is provided with a beveled lap 30 joint for maintaining the contiguous edges at the lap joint together during the expanding or contracting of the gasket as it is moved over the surface of piles of varying diameters.

Having thus described the various parts 35 of my apparatus, the application of the same is as follows: When a covering of concrete is desired to be placed around a pile or similar support and without removing any parts 40 of the superstructure resting on said pile, the reinforcing and supporting frame is opened, and placed in proper position by suspending the apparatus by means of chains or other suitable means depending 45 from the superstructure. The frame with the tubular mold casing therein, is then closed around the pile and properly fastened. The apparatus is then lowered until the upper end of the mold casing is left projecting sufficiently above the water line to 50 facilitate placing and suitably connecting another section of the tubular mold casing with the reinforcing frame attached thereto in alinement with the section already in 55 place.

In the apparatus shown, I provide clevises 22' which engage the uppermost annular shape hoop 9, of the section of the supporting frame already in place, and the annular 60 shaped hoop at the lower extremity of the second section of the supporting frame. The supporting frame with the tubular casings therein is again lowered until the uppermost end thereof protrudes a sufficient distance

above the water line to facilitate adding 65 thereto another section of the reinforcing frame and a section of the tubular mold casing.

At the outside of the lower tubular mold casing, I place vertically disposed pockets 70 into which are placed jetting tubes 12-12, which are added to and lengthened as the sections of tubular mold casings are added to the apparatus.

In this manner I continue increasing the length of the reinforcing frame, the tubular mold casing, and the jetting tubes, until the lower end of the apparatus has reached the bottom, and a portion 75 of the apparatus still remains above the water line.

When the bottom has been 80 reached, if found to be of such form as to require jetting, I provide suitable means for forcing water under pressure, into the jetting tubes 12-12, and the lower end of the tubular mold casing is made to penetrate 85

the bottom by the jetting process until a sufficient depth has been reached to insure a close contact between the bottom and the lower mold section to prevent the admission 90 of sea water from below.

When this state 95 has been accomplished the hose 13 with the nozzle 16 together with the gasket 17, attached thereto, is placed in the annular space between the tubular mold casing and the pile, and by suitable means is lowered to the 95

bottom of the casing by passing the hose 13 over a suitable sheave 20 which has been properly attached to and supported from the superstructure 22 resting upon the pile.

The sheave 20 is made of sufficient diameter 100 in that the hose 13 will not be liable to kink and cause a constricting of the passage way in being bent over the sheave. The upper

terminal of hose 13, is then attached to the ejecting apparatus 14, and fresh water 105 is placed therein and discharged through the hose 13 at the lowest point within the mold casing, thereby causing a substantial evacuation of the salt water or a sufficient diluting thereof, to avoid its disintegrating 110 effect on the concrete.

When this has been accomplished the ejecting apparatus 14 is filled with concrete, suitably mixed and is ejected under power. The apparatus 14, is 115 operated by suitable transmission connecting with motor 15, which is electrically driven from any convenient sources of electric power (not shown).

As the concrete is forced through the hose 120 13, and is ejected from the nozzle 16, it will deposit itself uniformly around the pile, and as the concrete fills up the annular space between the pile and the tubular casing, the gasket 17 with the discharge nozzle 16 attached thereto, will be automatically ele-

125 vated as the filling of the annular space continues, until the gasket 17 has risen above the level of the tide, and automatically dis-

- charged the sea water standing in the annular space between the pile and the tubular casing. To provide for conveying the concrete mixing and discharging apparatus 14, I provide a suitable lighter or pontoon 21, which can be moved about, between the rows of piling at any position desired.
- I do not limit myself to the specific forms of apparatus herein shown as other modifications thereof may be had without departing from the spirit of my invention.
- What I claim and desire to secure by Letters Patent is:
1. An apparatus for forming concrete casings around piles comprising means for providing an annular space around a pile consisting of a mold casing, means for discharging concrete under pressure from a portable discharging apparatus, means for conveying said concrete from the discharging apparatus to the bottom of the pile, and means for screening the water within the annular space around the pile from the concrete being discharged.
  2. The method of forming the concrete casing around piles, which consists in creating around a pile within the surrounding sea water an annular zone, conveying properly mixed concrete to a point below the surface of the water, shielding the concrete being discharged from the water within the annular zone, and evacuating the annular zone of sea water by replacing it with concrete.
  3. The method of forming the concrete casings around piles, which consists of creating around a pile within the surrounding sea water, an annular zone isolated from the surrounding sea water, conveying concrete through a flexible conduit to the bottom of the pile, extending the concrete to a point above the level of the tide, and screening the concrete from the water during said operation.
  4. An apparatus of the character described, comprising an annular mold around a pile means for extending said mold to the bottom of the pile, means for discharging concrete under pressure from a portable discharging apparatus, a flexible conduit leading from said discharging apparatus to the annular mold, and screening means adapted for vertical movement separating the water within said mold from the concrete therein.
  5. The method of forming a concrete casing around a pile which consists in creating around the pile within the surrounding sea water an annular zone, evacuating the sea water from said zone by filling said zone with fresh water, forcing plastic concrete under pressure into said zone, and causing the incoming concrete to elevate and discharge the water from said zone.

6. The method of forming a concrete casing around a pile which consists of creating around the pile within the surrounding sea water, an annular zone isolated from the surrounding sea water, evacuating the sea water from said zone, conveying concrete through a flexible conduit to the bottom of the zone and screening the concrete being discharged from the conduit, from the water within said zone.

7. The method of forming a concrete casing around a pile, which consists of creating around the pile within the surrounding sea water, an annular zone isolated from the surrounding sea water, evacuating the sea water from said zone, conveying concrete through a flexible conduit to the bottom of the zone, screening the concrete being discharged from the conduit, from the water within said zone and isolating the concrete from the surrounding sea water during its initial set.

8. The method of forming a concrete casing around a pile, which consists of creating around the pile within the surrounding sea water, an annular zone isolated from the surrounding sea water, evacuating the sea water from within said zone by filling said zone with fresh water, conveying concrete through a flexible conduit to the bottom of the zone and screening the concrete being discharged therein from the water within said zone.

9. In an apparatus of the character described, the combination of a supporting frame, a sectional tubular casing encircling a pile, means for extending said tubular casing to the bottom of the pile, jetting means for sinking said casing into the ground formation, means for substituting fresh water for salt water standing within said casing, a portable conduit extending within said casing to the bottom thereof, with means for discharging concrete through said conduit to fill said casing, and thereby automatically forcing the water therefrom.

10. The method of forming a concrete casing around a pile which consists in creating around a pile within the sea water, an annular zone, extending said zone to a point below the exterior surface of the ground formation into which the pile is driven, evacuating the sea water from said zone by a replacement thereof of fresh water and filling said zone with plastic concrete.

11. The method of forming a concrete casing around a pile which consists in creating around a pile within the surrounding sea water, an annular zone, extending said zone below the ground formation, evacuating the sea water from said zone by filling said zone with fresh water, placing plastic concrete at a point within said zone below the surface of the water, and discharging the

water from said zone by the concrete filling operation.

12. An apparatus of the character described comprising portable sea water screening means, portable concrete forcing means, portable concrete molding means, mold lowering means, sea water evacuating means, and means for removing the molding means after the concrete has received its initial set.

13. An apparatus for forming concrete casings around piles comprising means for creating an annular zone around a driven pile, means for extending said zone into the ground formation into which the pile is driven, means for depositing under pressure plastic concrete under the column of water within said annular zone and means for shielding the water from the concrete during said depositing operation.

14. In an apparatus of the character described the combination of means for isolating an annular zone within the sea water surrounding a driven pile, means for depositing

concrete under pressure under the columns of water within said annular zone, and means for screening the column of water from the concrete during the concrete depositing operation.

15. In an apparatus of the character described the combination of means for isolating an annular zone within sea water surrounding a driven pile, means for extending said zone into the ground formation into which the pile is driven, means for depositing concrete under pressure under the column of water within said annular zone, and screening means separating said column of water from the concrete adapted for vertical movement during the depositing operation.

In testimony whereof I have affixed my signature in presence of two witnesses.

EDWARD W. SCOWDEN.
